Carl E. Fornes,

Inventor:
Wm. C. P. Stevens

UNITED STATES PATENT OFFICE.

ENOCH P. STEVENS, OF CHICAGO, ILLINOIS, ASSIGNOR TO AMERICAN ARCH COMPANY, OF NEW YORK, N. Y., A CORPORATION OF DELAWARE.

CANTALIVER-MARGIN FOR LOCOMOTIVE-ARCHES.

1,229,391.

Specification of Letters Patent. Patented June 12, 1917.

Application filed February 11, 1916. Serial No. 77,648.

To all whom it may concern:

Be it known that I, ENOCH P. STEVENS, a citizen of the United States, and a resident of Chicago, county of Cook, and State 5 of Illinois, have invented certain new and useful Improvements in Cantaliver-Margins for Locomotive-Arches, of which the following is a specification.

My invention relates to refractory brick 10 arch constructions for the fireboxes of steam locomotives.

The invention herein described may be best classified as an improvement upon, or modification of, the cantaliver arch brick 15 construction described and claimed in my prior application, Serial No. 757,822, originally filed March 31st, 1913, Serial No. 757,822, and renewed January 10, 1916, Series of 1915, No. 71,378.

20 The object of this present invention is to provide a locomotive firebox arch of the type composed of refractory bricks supported by spaced arch tubes, and in which the marginal bricks, namely, the bricks which 25 occupy the spaces between the outer arch tubes and the side sheets of the firebox, shall be engaged with or supported by the main or body bricks of the arch in such manner as to be held in position independently of 30 said side sheets.

In carrying out my invention I form the body bricks of the arch in a manner to provide them with stops or lugs on, or at, their tops, and with such bricks I combine separate marginal bricks which are formed to engage over said lugs or stops in manner to be rigidly sustained by the same and the supporting arch tubes, whereby said marginal bricks are supported in close proximity to respective side sheets of the firebox but without assistance therefrom.

The general nature of my invention, as well as the details thereof, will be readily understood on reference to the drawings 45 which form part of this specification, in which I have depicted the construction I prefer, together with several modifications thereof.

In said drawings, Figure 1 is a longitudinal vertical section of a locomotive firebox containing an inclined front arch embodying my invention;—Fig. 2 is a transverse section on the line Z—Z of Fig. 1;—Fig. 3 is a side view of one of the cantaliver 55 bricks;—Fig. 4 is a top view thereof;—Fig.

5 is a top view of one of the body bricks shown in Fig. 2;—Fig. 6 is a sectional view similar to Fig. 2 but showing the invention in modified form;—Fig. 7 is a side view of one of the cantaliver bricks shown in Fig. 6;—Fig. 8 is an inner end view thereof;—Fig. 9 is an outer end view thereof;—Fig. 10 depicts the bottom thereof;—Fig. 11 is a top view of one of the body bricks shown in Fig. 6;—Fig. 12 is a view similar to Fig. 2, showing still another modification of the invention;—Fig. 13 is a side view of the cantaliver brick disclosed in Fig. 12;—Fig. 14 is an inner end view of said brick;—Fig. 15 is an outer end view thereof;—Fig. 16 depicts the bottom thereof;—and Fig. 17 is a top view of one of the body bricks shown in Fig. 12.

The familiar parts of a locomotive are as follows: The grate, 2;—the mud ring, 3;—the rear sheet, 4;—the flue sheet, 5;—the crown sheet, 6;—side sheets, 7, 7;—and the inclined water circulating arch tubes, 8. Reference is also made to the boiler shell indicated at 9;—to the fuel door opening, 10;—and to the flues, 11. As shown in Figs. 2, 6, and 12, there are several arch tubes, 8, the same being spaced across the firebox. The body portion of the refractory arch is composed of fire bricks, A, which rest upon 85 and close the spaces between the tubes, 8. The outermost tubes are not placed directly against the side sheets, but are spaced therefrom a considerable distance, to afford free access to the stay-bolts (not shown) of the 90 side sheets. However, the space between an outer tube and adjacent side sheet is usually less than the space between the several tubes, 8. In other words, the body bricks, A, practically in all cases are of much 95 greater length than the spaces, α , between the outer tubes and the side sheets. This being the case, such body bricks, A, cannot well be used to close the spaces, α , and it is necessary to provide bricks of other forms 100 for that purpose. These bricks are commonly referred to as side bricks or marginal bricks. It is the usual practice to make the marginal bricks to rest either upon the ends of the outermost body bricks, A, or upon 105 the outer arch tubes, and also to rest against the side sheets of the firebox.

The purpose of this invention is to avoid depending upon the side sheets as support for the marginal bricks, and to this end I 110

construct the marginal bricks in such manner that they are entirely supported by the body of the arch and do not require the assistance of the firebox sides. In referring 5 to the body of the arch, I mean the arch proper which is made up of the arch tubes, 8, and the body bricks, A. The bricks, A, which constitute the major portion of the arch body are herein differentiated by the 10 name main or body bricks.

As the marginal bricks are thus supported by and project outwardly from the arch body, they are appropriately called cantaliver bricks. The several marginal bricks 15 shown in the drawings are indicated by the common reference letter, B. In general, I prefer that each marginal brick shall be engaged with the ends of the two body bricks, A, but the following description will show 20 that single body bricks may support or coact with respectively individual cantaliver marginal bricks.

The several examples depicted in Figs. 2 to 17 clearly disclose the fact that the 25 herein described desirable functions may be performed by body bricks and cantaliver bricks of various forms and which are interlocked in various ways.

Referring now to Figs. 2 to 5, inclusive,— 30 the body bricks there shown correspond with those depicted in Fig. 1. Where four arch tubes are used, the middle body brick, A', may be of any desired form. This is true in all the cases shown. Each of 35 the body bricks, a, of Fig. 2, has its outer end formed with a socket or groove, a', which substantially fits the top of the outermost arch tube, 8. On the top of the brick is an upstanding lug a², which may extend 40 entirely across the brick, as shown in Fig. 5. The extreme end presents a preferably inclined bracing surface, a³. To interlock and coact with a body brick of the described construction, I provide a cantaliver brick, 45 b, which has a groove, b', in its under side, and the inner end, b², of which comprises a hook which engages over the lug or stop, a². The intermediately positioned depending part, b³, is shaped to rest against the 50 shoulder, a⁴, of the body brick. From that point the brick extends outwardly and terminates just short of the side sheet, 7. The under surface, b⁴, is preferably inclined from the part, b³, to the point, b⁵. The 55 brick may be lightened and also made to serve as a gas-mixing device by providing it with a gas-mixing pocket, b⁶, in its under surface. An advantage of the construction shown in Fig. 2 is that the bricks, b, may 60 be moved on the longitudinally extended seat formed by the lugs or ribs, a², and shoulders, a³, of several body bricks. In other words, the brick, b, need not be fastened in any given longitudinal position on 65 the top of the arch.

In contrast with the feature last above mentioned, I may form the cantaliver bricks in manner to be held against movement longitudinally with respect to the body bricks and supporting tube. This advantage may be secured by using a body brick, c, which is provided with a recess, c', in its top near its outer end. The presence of this recess provides a lug or stop portion, c², for engagement with the cantaliver 70 brick, d. The brick, d, is provided with a hook-like lug, d', to co-act with the lug, c², and with a shoulder, d², to co-act with the outer side of the tube, 8'. I prefer that the recesses, d³, in the outer end of the brick 75 shall be formed in the sides of the brick, and leave a middle strut portion, d⁴; in contrast with the recess, b⁶, of the brick, b. Before leaving the discussion of Figs. 80 6 to 11, I call attention to the fact that the body bricks, c, contain symmetrical recesses, c', and also an opposed recess, c³. Where this design is used, all of the body bricks 85 of the arch may be of the same form, there being no projections beyond the main outlines of the bricks to interfere with their use in any of several positions.

A further modification, shown in Figs. 12 to 17, comprises body bricks, e, of the arched or upwardly bowed type, and cantaliver 90 bricks, f, of a form nicely adapted for use with such body bricks. The body brick, e, is provided with an upstanding lug, e', over which the cantaliver brick, f, hooks. The brick, f, is distinguished by two sides, 100 f', by an inner-end hook-portion, f², and by curved seats, f³. The latter are shaped to rest upon the top of the brick, e, and preferably extend to a low point against the side of the arch tube, 8".

It will be noted that in all of the cantaliver brick arch constructions here depicted, the cantaliver brick is characterized by a hanging hook at its inner end, adapted to engage an upstanding stop or lug formed 110 in or on the complementary body brick or bricks, and no support is required from the firebox side sheets.

As various modifications of my invention will readily suggest themselves to one 115 who is skilled in the art, I do not limit the invention to the specific constructions herein shown and described.

Having thus described my invention, I claim as new and desire to secure by Letters Patent:—

1. The locomotive firebox and its contained arch tubes, in combination with a refractory arch body supported by said tubes and composed of a plurality of longitudinal rows of bricks, the outer end of each brick in each outer row having upon its top a cantaliver-brick-engaging stop, cantaliver bricks adapted for support from their inner ends only and each having upon 130

its inner end a down-turned hook for engagement with the stop upon a respective body brick, and each cantaliver brick also having upon its inner end a depending stop portion which contributes to its support.

2. In a locomotive firebox arch, a body brick having an upstanding stop on its end, in combination with a cantaliver marginal brick formed with a down-turned hook on its inner end to engage over said stop on the body brick and provided with a depending stop portion for co-action with an arch tube to support said cantaliver brick.

3. In a locomotive firebox arch, a body brick having an upstanding stop on its end, in combination with a cantaliver marginal

brick formed with a down-turned hook on its inner end to engage over said stop on the body brick and provided with a depending stop portion for co-action with the end of the body brick and an arch tube to support said cantaliver brick.

4. In a locomotive firebox arch, a cantaliver marginal brick formed with a down-turned hook on its inner end to engage a body brick, and provided with a depending stop portion for co-action with the end of a body brick and the outer side of an arch tube to support said cantaliver brick.

In testimony whereof, I have hereunto set my hand this 8th day of January, 1916.

ENOCH P. STEVENS.
